WITNESS:

UNITED STATES PATENT OFFICE.

GEORGE B. VERNON, OF PHILADELPHIA, PENNSYLVANIA.

GRINDING MACHINE.

1,412,725.

Specification of Letters Patent. Patented Apr. 11, 1922.

Application filed July 10, 1920. Serial No. 395,216.

To all whom it may concern:

Be it known that I, GEORGE B. VERNON, a citizen of the United States, residing at Philadelphia, in the county of Philadelphia and State of Pennsylvania, have invented 5 new and useful Improvements in Grinding Machines, of which the following is a specification.

The invention relates to grinding and 10 polishing and has for an object to provide a machine for use in grinding and polishing stone-work, masonry, marble and other surfaces.

The invention is particularly adapted for 15 use on the walls of brick buildings and the like and in places where marble slabs are used to grind off worn or projecting surfaces and obtain a smooth, neat appearing finish. Still further the invention comprehends 20 a grinding machine in which a rapidly rotating abrasive member is employed for the cutting, grinding or polishing operation. To this end the machine is preferably power driven so that the grinding operation can 25 be quickly and effectively accomplished, thus doing away with the present method of grinding the surfaces of bricks and the like and the sides and walls of buildings and which is now usually accomplished by 30 hand.

In the further disclosure of the invention, reference is to be had to the accompanying drawings constituting a part of this specification, in which similar characters of reference denote corresponding parts in all the 35 views, and in which,—

Figure 1 is an end view of the machine.

Figure 2 is a front view.

Figure 3 is a vertical sectional view taken 40 on the line 3—3 in Figure 2, and

Figure 4 is a horizontal sectional view taken on the line 4—4 in Figure 2.

Referring more particularly to the views, I provide a box or casing 10, the front 11 of which is formed with an opening 12 through which projects a portion of an abrasive or polishing member 13 which may be in the nature of a buffer or a grinding stone formed of carborundum or some other 45 similar material. The box is provided at its rear with a handle 14 for the ready manipulation of the box so that it can be held against the wall of a building, bringing the surface of the member 13 in contact with the 50 building. The grinding stone or member has a vertical shaft or spindle 15 passing

therethrough and also through bearings 16 with suitable nuts 17 threaded on to the shaft to bear against the ends of the member 13 making the same rigid with the 60 shaft so that it will rotate therewith. The washers 18, nuts 19 and lock nuts 20 are arranged upon a shaft to mount the same in the bearings 16 and the lower end of the shaft has connection through the medium 65 of a coupling 21 with a flexible shafting 22 connecting with a suitable motor 23, whereby the member 13 can be rapidly rotated. Within the box there is provided a guard 24 which serves to direct the dust 70 produced in the grinding operation, toward an opening 25 in the lower part of the box and with which there is connected a hose 26 connecting with the motor 23, and preferably with a suction fan 27 driven by a 75 motor so that the dust or particles of stone or brick which are ground away by the member 13 will be carried off to a suitable place of disposal. The back or rear side 28 of the box has fitted therein a plurality 80 of nuts 29 through which are threaded stems or rods 30, the outer ends of which carry suitable handles 31 and the inner ends of which are provided with heads 32 received in slots 33 in the bearings 16, the bearings 85 in turn being arranged in slotted portions 34 of the box and formed also with plates 35 substantially covering the slotted portions of the box.

Now it will be apparent that when the 90 operator places the box against the wall, he can by turning the handles 31, move the grinding member toward or away from the surface to be operated upon and can move one end of the grinding member slightly 95 toward or away from the surface more than the other end by reason of the upper and lower adjusting screws and screw rods set out, it being of course very evident that the slight angularity of adjustment that might 100 be desired as to the grinding member is almost infinitesimal and can be readily accomplished with the mounting set out.

It will readily be seen that by removing the lock nuts 20, nuts 19 and washers 18, 105 that the bearings 16 can be removed so that the grinding member 13 can be taken out of the box when the back 28 is removed in order that the grinding member may be replaced by one of a finer or rougher quality 110 or grade, or a buffer may be employed in place of the abrasive member.

Although I have shown a particular form of structure, it will be understood that I do not limit myself to the particular details of construction as set out in the drawings and described in this specification, and that various slight changes may be made without departing from the spirit of the invention, the scope of which is defined in the appended claim.

- 10 Having described my invention, I claim—
A grinding machine comprising a casing, bearings adjustably mounted in the upper and lower walls of the casing, a shaft mounted in the bearings, a roller mounted 15 on the shaft and normally retained in a vertical position during operation, permitting waste material to fall to the lower por-

tion of the casing, means for withdrawing said waste material by suction, and a curved element of sheet material, cooperating with 20 one wall of the casing for enclosing the roller, the lower wall of said casing being provided with a segmental slot, the curvature of which conforms to the curvature of the roller and the curved element surrounding the latter, the slot being in communication with the means for withdrawing waste material, said segmental slot being positioned between the curved element and roller and producing an air current enveloping a 25 segment of the roller and moving longitudinally thereof from bottom to top.

In testimony whereof I affix my signature.
GEORGE B. VERNON.
